DANCE GLIDING DEVICE

Everett R. Shaw, Tempe, Ariz.

Application March 21, 1949, Serial No. 82,550

5 Claims. (Cl. 36—8.3)

1

My invention relates to dancing shoes and has for its general object the provision of devices whereby glides or sliding movements over great distances may be carried out on dancing floors.

The invention may be incorporated in specially designed dance shoes, but is hereinafter described, by way of example, in the form of attachments for shoes of ordinary construction.

It is an object of my invention to provide means whereby gliding or sliding movements of the wearer over extended distances may be achieved under full control of the dancer and enabling him to execute ordinary steps and extended glides or slides with as much facility as when executing ordinary dance steps when wearing ordinary shoes.

Yet other objects of my invention are to provide footwear for dancing by which novel gliding steps may be executed which footwear may be produced as shoes incorporating novel features, or in the form of attachments available in various forms, which may be readily secured to a shoe and removed therefrom without requiring any modification of the conventional shoe, and which attachments are both light and inexpensive.

Still further objects and features of my invention will hereinafter appear from the following specification taken in conjunction with the accompanying drawings in which are illustrated embodiments of the invention at present deemed preferable by me, but it is to be understood that various modifications and changes may be made in the illustrated embodiments by those skilled in the art without departing from the scope of the invention as intended to be defined by the appended claims.

In the accompanying drawings:

Fig. 1 is a perspective view of the gliding element of my invention formed as a separate fitting and including shank and heel portions formed as an integral unit.

Fig. 2 is a side elevation showing the gliding fitting of Fig. 1 mounted on a shoe and in use for a gliding dance step.

Fig. 3 is a side elevation similar to Fig. 2 but showing how the fitting is carried, in ordinary dance steps, out of contact with the floor.

Fig. 4 is a perspective view showing a modified form of the fitting formed from a block of hard resin or other suitable material and adapted to be secured under the shank only of a shoe.

Fig. 5 is a side elevation showing the device of Fig. 4 in use in a gliding dance step.

Fig. 6 is a perspective view of another modified form of my invention.

2

Fig. 7 is a side elevation showing the modified form of my invention illustrated in Fig. 6 in position on a shoe and in use for a gliding dance step.

5 Fig. 8 is a cross section on the line 8—8 of Fig. 6.

Referring now to Fig. 1, the gliding device is illustrated as formed, for instance by molding plastic material, to provide a unitary body 10 providing a flat low friction floor engaging surface 12 with a rearward extension or plate 13 covering the heel 14 of the shoe and extending forwardly over the shank 16 of the shoe to the back of the sole 18 of the shoe which underlies the "ball" 15 or metatarsal region of the wearer's foot. It will be noted that the level of the floor engaging surface is slightly below the level of the lower surface of the sole, the front end 20 being curved upwardly to meet the rear edge of the sole. Since 20 it is necessary to provide a snug fit of the device on the shoe, I form or mold the body to accurately follow the contour, in plan, of the heel and shank of a shoe, as well as to follow the curves of the bottom portions of the shoe, this feature requiring the provision of left and right fittings for 25 left and right shoes. It will be noted that an upstanding wall 22 is provided to fit snugly against the forward vertical face of the heel of the shoe and that the upper surface of the body 10 is curved, as indicated at 24, to lie against the underside of the shank. Since the lower face of a shoe shank is often transversely curved a transverse inward curve is formed in the upper surface of the fitting engaging below the instep, the transverse curve flattening out toward the rear.

I provide means for securely but detachably holding the fitting in position on the wearer's shoe and while such holding means may be of any suitable arrangement, it has been found that a pair of ties, such as strong ribbons 28, 30 passed through holes 32 passing from side through the body and tied over the back of the shoe and over the shank will serve the purpose well.

In use in a gliding step with one or both feet 45 along the floor as shown in Fig. 2 it will be noted that the sole of the shoe is held slightly off the floor although the weight of the dancer is carried on his shank and heel which is a natural posture not fatiguing to the dancer, while the glide may be arrested at any time by the dancer merely leaning forward slightly to bring the sole of the shoe into contact with the floor. While doing ordinary dance steps, which for the most part are carried out with the dancer's weight on the ball of his foot and toes, the heel is slightly raised, as shown in Fig. 3, which brings the de-

vice out of contact with the floor, and the dancer is thus enabled to mingle novel gliding steps of both feet with ordinary dance steps.

The modified form of my invention shown in Figs. 4 and 5 may be formed from a block of hard resin and differs only from that shown in Fig. 1 in that the heel plate 13 is omitted, the body 10a being otherwise formed as previously described and similarly attached to a shoe as shown in Fig. 5, by laces 28a, 30a passing through holes 32a in the body. The gliding action will not be quite as good in this form of the invention because of the greater pressure on the body caused by the weight being carried on a smaller area.

In the further modification of my invention shown in Figs. 6 and 7 I provide additional positioning means to the laces 28b, 30b to hold the heel plate 13b securely on the heel 14 of a shoe. The additional positioning means may be formed as a peripheral flange 34 projecting upwardly from the heel plate 13b, which flange fits closely around the bottom edge of the heel 14 of the shoe as indicated in Fig. 7. The other features of the form of the invention shown in Fig. 6 are the same as described with reference to Fig. 1.

In this form of the invention the heel plate will of course be made sufficiently larger than the heel of the shoe to provide the extra width required for the flange 34.

In Fig. 8 longitudinal parallel grooves 36 are shown cut into the floor engaging face of the gliding fitting shown in Fig. 6, though of course I may provide such parallel grooves if desired in the other forms of the invention illustrated. The grooves 36 act to give a slightly better and straighter gliding motion than when the face of the fitting is completely flat.

It will be noted that when using the sliding attachment of my invention no extra strain is thrown on the dancer's feet since the area of flat surface in contact with the floor is ample at all times and, therefore, does not call for any extra balancing effort. The weight of the device is negligible so that the ease of movement of the dancer is not impaired, nor is his confidence, since the sliding effect can be checked with at any time by merely bringing the sole of the foot down upon the floor.

The use of my gliding attachment while dancing enables the dancer to widely increase the variety of steps and evolutions at his command and thus increases the interest and enjoyment derived from this pastime.

The gliding attachment of my invention may be made of metal such as aluminum, brass, magnesium or alloys thereof or of plastic of suitable characteristics with the floor engaging surface preferably waxed to reduce friction between it and the waxed dance floor. The low frictional surface may also be provided by a block of hard resin inserted in a metal frame having one or other of the forms above described, and various other obvious modifications will be apparent to those skilled in the art.

What I claim is:

1. A gliding attachment for shoes used for dancing, comprising: a body adapted to fit under the shank of the shoe, an upper surface on said body having a contour conforming to the contour of the shank of the shoe, and a floor engaging flat surface projecting slightly below the sole of the shoe; a rearwardly projecting plate

like extension of said body extending over the heel of the shoe, said extension having a flat floor engaging surface in the same plane as the floor engaging of the body; an upstanding flange 5 projecting from the perimeter of said plate like portion and abutting the sides and back of the heel of the shoe; and readily releasable means for securing the attachment in position on the shoe.

10 2. A gliding device for shoes used for dancing, comprising: a body having a smooth floor-engaging surface of low frictional characteristics positioned under the shank of the shoe and extending to a level slightly below the level of the heel and sole of the shoe; and means securing 15 said body in position on the shoe, whereby gliding movements of extended length may be executed while the sole of the shoe is out of contact with the floor, and usual dance steps 20 may be executed with the sole of the shoe resting on the floor with the device raised out of contact with the floor, and longitudinally extending grooves in said floor engaging surface.

25 3. A gliding element for shoes used for dancing, comprising a body having a smooth floor-contacting flat surface of low frictional characteristics extending under the shank of the shoe and completely over the bottom face of the heel portion of the shoe, said body terminating at 30 its forward end substantially at the rear end of the fore-sole portion of the shoe, the shank and heel portions of said body providing a sliding surface extending slightly below the level of the tread area of the fore-sole portion of the shoe 35 and terminating substantially at the rear end thereof.

4. A gliding attachment for shoes used for dancing, comprising a body adapted to fit under the shank of the shoe having an upper surface 40 of a contour conforming to the contour of the shank of the shoe, said body terminating at its forward end substantially at the rear end of the fore-sole portion of the shoe and having a floor engaging flat surface projecting slightly below the fore-sole portion of the shoe, the body having a rearwardly projecting plate-like extension 45 extending substantially completely over the heel portion of the shoe, said extension having a flat floor engaging surface in the same plane as the floor engaging surface of said body, and means for readily connecting and disconnecting the attachment and the shoe.

5. A gliding attachment for shoes of the construction defined in claim 4 and in which the floor 55 engaging flat surface of the body is curved at its forward end upwardly to the forward end of the upper surface of said body to allow for smooth transition in lowering the heel to bring the attachment into play.
